(57) **CLAIM**

The ornamental design for a bottle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a bottle, embodying our new design according to a first embodiment;

FIG. 2 is a back perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and

FIG. 8 is a bottom view thereof;

FIG. 9 is a front perspective view of a bottle, embodying our new design according to a second embodiment;

FIG. 10 is a back perspective view thereof;

FIG. 11 is a front view thereof;

FIG. 12 is a back view thereof;

FIG. 13 is a first side view thereof;

FIG. 14 is a second side view thereof;

FIG. 15 is a top view thereof; and

FIG. 16 is a bottom view thereof.

FIG. 17 is a front perspective view of a bottle, embodying our new design according to a third embodiment;

FIG. 18 is a back perspective view thereof;

FIG. 19 is a front view thereof;

FIG. 20 is a back view thereof;

FIG. 21 is a first side view thereof;

FIG. 22 is a second side view thereof;

FIG. 23 is a top view thereof; and

(Continued)

FIG. 24 is a bottom view thereof.
 FIG. 25 is a front perspective view of a bottle, embodying our new design according to a fourth embodiment;
 FIG. 26 is a back perspective view thereof;
 FIG. 27 is a front view thereof;
 FIG. 28 is a back view thereof;
 FIG. 29 is a first side view thereof;
 FIG. 30 is a second side view thereof;
 FIG. 31 is a top view thereof; and
 FIG. 32 is a bottom view thereof.
 FIG. 33 is a front perspective view of an embossed bottle, embodying our new design according to a fifth embodiment;
 FIG. 34 is a back perspective view thereof;
 FIG. 35 is a front view thereof;
 FIG. 36 is a back view thereof;
 FIG. 37 is a first side view thereof;
 FIG. 38 is a second side view thereof;
 FIG. 39 is a top view thereof; and
 FIG. 40 is a bottom view thereof.
 FIG. 41 is a front perspective view of a bottle, embodying our new design according to a sixth embodiment;
 FIG. 42 is a back perspective view thereof;
 FIG. 43 is a front view thereof;
 FIG. 44 is a back view thereof;
 FIG. 45 is a first side view thereof;
 FIG. 46 is a second side view thereof;
 FIG. 47 is a top view thereof; and
 FIG. 48 is a bottom view thereof.
 FIG. 49 is a perspective view of an embossed bottle, embodying our new design according to a seventh embodiment;
 FIG. 50 is a front view thereof;
 FIG. 51 is a back view thereof;
 FIG. 52 is a first side view thereof;
 FIG. 53 is a second side view thereof;
 FIG. 54 is a top view thereof; and
 FIG. 55 is a bottom view thereof.
 FIG. 56 is a perspective view of an embossed bottle, embodying our new design according to an eighth embodiment;
 FIG. 57 is a front view thereof;
 FIG. 58 is a back view thereof;
 FIG. 59 is a first side view thereof;
 FIG. 60 is a second side view thereof;
 FIG. 61 is a top view thereof; and
 FIG. 62 is a bottom view thereof.
 The broken lines shown in the drawings form no part of the claimed design.
